Primary Examiner — Steven J Czyz*(74) Attorney, Agent, or Firm* — Wissing Miller LLP(57) **CLAIM**

The ornamental design for a trade show booth display, as shown and described.

DESCRIPTION

FIG. 1 is a front perspective view of a trade show booth display in accordance with the present design; FIG. 2 is a side perspective view thereof; FIG. 3 is a side perspective view thereof; FIG. 4 is a side perspective view thereof; and FIG. 5 is a top view thereof; and, FIG. 6 is another side perspective view thereof. The broken lines depict portions of the article that form no part of the claimed design. The shading represents contour of the claimed design.
